Primary Examiner — Susan Bennett Hattan*Assistant Examiner* — Brett Miller*(74) Attorney, Agent, or Firm* — Leason Ellis LLP(57) **CLAIM**

I claim the ornamental design for a multi-function grill machine, as shown.

DESCRIPTION

FIG. 1 is a front elevation view of a multi-function grill machine showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front, left, top perspective view of the grill in a closed position for the first using state; and,

FIG. 8 is a front, left, top perspective view of the grill in an open position for the second using state.
